UNITED STATES PATENT OFFICE.

GUY REYNOLDS JAMES, OF ROME, MISSISSIPPI.

METAL CROSS-TIE.

No. 851,810.

Specification of Letters Patent.

Patented April 30, 1907.

Application filed August 31, 1906, Serial No. 332,813.

To all whom it may concern:

Be it known that I, GUY REYNOLDS JAMES, a citizen of the United States, residing at Rome, in the county of Sunflower and the State of Mississippi, have invented a new and useful Improvement in Metal Cross-Ties, of which the following is a specification.

This invention relates to a metal tie for railroads, and the object of the invention is a tie having no wearing portions in the tie proper, and so constructed that all portions liable to wear can be readily replaced by new parts without removing the tie from position.

The invention consists in the novel features of construction and parts hereinafter described, pointed out in the claims and shown in the accompanying drawings in which:—

Figure 1 is a perspective view of a tie in place. Fig. 2 is a perspective view of a portion of a tie not in use, a wear plate being removed. Figs. 3 and 4 are perspective views of clamps. Fig. 5 is a section through a partition carried by the tie and transversely through a rail. Fig. 6 is a modified form of clamp or tie plate. Fig. 7 is a perspective view of a plate used with the form shown in Fig. 6. Fig. 8 is a longitudinal section through the tie. Fig. 9 is a plan view of the tie, wear plates being omitted. Fig. 10 is a transverse section through the tie, a portion of a partition being shown in section. Fig. 11 is a transverse section through one of the partitions and through a wear plate. Fig. 12 is a perspective view of a wear plate detached.

In these drawings A represents the tie which is in the form of a metal trough with open, beveled ends. In this tie in position to form a support for the rails are partitions A', preferably integral with the tie. These partitions are wedge-shape in cross section, as shown, and terminate short of the top of the sides of the tie, which sides are cut away adjacent or at the ends of the partitions as shown at A² to receive the rails. The partitions A' have wedge-shaped recesses A³ in their upper faces and are also provided with transverse slots A⁴.

To secure the rails in place I employ clamps B having inclined inner faces to conform to the faces of the partitions and having their upper, thinner ends bent over as shown at B' to engage the base of the rails.

A wedge-shaped piece of comparatively soft metal C is inserted in each recess A³ and

the upper face of this piece C projects slightly above the face of the partition, and supports the rail. These pieces C form wear plates and being soft prevent longitudinal creeping of the tie.

I may also employ a tie plate D where joints break at or near a tie, in which event a clamp D' is formed integral with the tie plate D and takes the place of one of the clamps B, a straight tie plate D² and one of the clamps B being used on the opposite side of the rail, as shown in Fig. 5. I also prefer to press the bottom of the tie midway its ends, as shown at E, inwardly.

In use the rails rest on the wear plates C and are held by the clamps B and at joints by clamps D' and B. These clamps are secured to the partitions A' by bolts F which pass through the perforations or slots A⁴, and it will be noted that these slots are of sufficient size to allow free vertical movement of the bolts, when loosened, so that the clamps B, or D', may be adjusted vertically to allow for wear or varying thickness of the rail base, 80 the base being engaged by the bent portion B'.

The elevated portion E aids in the drainage of the tie by shedding water to the ends of the tie which are open to permit thorough drainage. On covered bridges, underground 85 roads, tunnel work etc. these ridges at E are not required.

To facilitate the attachment of the ties to bridges, trestles etc. perforations G may be formed to receive spikes.

It will be understood from the above that the ridges E and perforations G are not essential features of all of the ties but adapt them for service under special conditions. It will also be understood that at switch 95 points the ties are longer than ordinary ties, as in case of wooden ties in present use at switches, and ties used at such points may have three, four or more partitions A' to each tie A.

The ties are also provided with drainage openings H between the partitions A' and the central elevations or ridges E as shown in the plan view. The elevation E forms a recess under the tie which serves to prevent longitudinal creeping of the tie upon the road bed.

Having thus fully described my invention what I claim as new and desire to protect by Letters Patent is:

1. A tie comprising a trough having transverse partitions, a wear plate secured on each

- partition to support a rail, and means for locking the rail to each partition.
2. A tie of the kind described comprising an open trough, transverse partitions therein, recesses being formed in the tops of the partitions, wear plates in said recesses adapted to support rails, clamps adapted to engage the rail bases and bearing on the sides of the partitions, and means for adjustably locking the clamps to said partitions.
3. A device of the kind described comprising a trough, wedge-shaped partitions therein, said partitions having top recesses and side slots, plates of comparatively soft metal in the recesses, and clamps adapted to engage the sides of the partitions and the base of a rail, as and for the purpose set forth.
4. A metal tie having the form of a trough, partitions therein terminating short of the tops of the trough sides, said sides being cut out at the ends of the partitions to receive rail bases, metal wear plates carried in the recesses formed in the partitions, and vertically adjustable clamps adapted to bind the rail bases to the partitions.
5. A device of the kind described comprising a trough open at the ends and having a central elevation and having bottom perforations, vertical partitions in said trough, the sides of the trough being cut out adjacent the ends of the partitions, wear plates carried by and projecting above the tops of the partitions, and vertically adjustable clamps con-
- nected to the partitions and adapted to engage rail bases.
6. A device of the kind described comprising a trough open at the ends, slightly elevated at its center, and having integral transverse partitions on opposite sides of the central elevation, and having its bottom perforated between the central elevation and the partition, and the sides cut away at the ends of the partitions.
7. A tie having the form of a trough, wedge shaped partitions formed transversely therein, the sides of the tie being cut away at the ends of the partition, the partition having a wedge-shaped recess formed in its top, a piece of comparatively soft metal inserted in said recess and extending above the top of the partition, and means for locking a rail to said tie, the rail base resting on said soft metal.
8. A tie having the form of a trough, transverse wedge-shaped partitions therein, said partitions being transversely slotted, clamps having inclined inner faces to conform to the sides of the partitions and bent over to engage the base of a rail, and bolts passing through said clamps and slots, and having free play in the slots for vertical adjustment of the clamps.
